Primary Examiner — George J Ulsh*Assistant Examiner* — Kathryn Elizabeth Chambers(74) *Attorney, Agent, or Firm* — CANTOR COLBURN LLP(57) **CLAIM**

The ornamental design for a lamp for a vehicle, as shown and described.

DESCRIPTION

FIG. 1 is a top-front-left perspective view of a lamp for a vehicle showing my new design;

FIG. 2 is a top-rear-right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrate portions of the lamp for a vehicle that form no part of the claimed design.
